UNITED STATES PATENT OFFICE.

MAX SCHNEFEL, OF NEWARK, NEW JERSEY, ASSIGNOR TO SCHNEFEL BROTHERS, A FIRM COMPOSED OF MAX SCHNEFEL AND CARL SCHNEFEL, OF NEWARK, NEW JERSEY.

DESIGN FOR A TWEEZERS OR SIMILAR ARTICLE.

Application filed September 19, 1925. Serial No. 14,824. Term of patent 7 years.

To all whom it may concern:

Be it known that I, MAX SCHNEFEL, a citizen of the United States, and a resident of Newark, in the county of Essex and State of New Jersey, have invented a new, original, and ornamental Design for Tweezers or Similar Articles, of which the following is a specification, reference being had to the accompanying drawing, forming part thereof.

Figure 1 is a plan view of a tweezers displaying my new design;

Figures 2 and 3 are cross-sections taken on the lines 2—2 and 3—3, respectively, of Figure 1; to show the design more clearly, and

Figure 4 is a side elevation of the tweezers on a reduced scale.

I claim:

The ornamental design for a tweezers or similar article, as shown.

MAX SCHNEFEL.
